MINING MACHINE ANCHORING MECHANISM

Frederick B. Miller, Chicago, Ill.; Mary W. Miller, executrix of the estate of said Frederick B. Miller, deceased

Application June 29, 1950, Serial No. 171,135

10 Claims. (Cl. 262—9)

This invention relates to a machine adapted to undercut coal, break down the coal undercut, and load the coal cuttings from the undercut and the coal broken down above the undercut.

Among the objects of my invention is to provide an improved and efficient form of anchor for releasably anchoring a coal mining machine to the floor of the mine, whereby the machine will effectively resist the reactive force of the wedge plate caused by forward thrusts of the same in breaking down the coal at the mine face.

A further object is to provide anchoring mechanism for a coal mining machine including a pivoted anchor bar carried by the forward kerf cutting end of the machine, said pivoted anchor bar in pressing against the floor of the mine causing the kerf cutting forward end to press against the top side of the kerf with an equal and opposite force, whereby the combined action of said anchor bar and the kerf cutting forward end locks the machine in coal mining position.

These and other objects will be apparent after referring to the accompanying drawings, in which

Figure 1 is a plan view of the machine;

Figure 2 is a side elevation of the machine taken on line II—II of Figure 1 and in part section showing the detail of the hydraulic jack in conjunction with an anchor bar pressed against the floor of the mine;

Figure 3 is an end elevation of the machine taken on line III—III of Figure 1;

Figure 4 is a transverse section of the conveyor taken on line IV—IV of Figure 1 showing the conveyor in relation to the cutter chains;

Figure 5 is a fragmentary detail, in part elevation and in part section on line V—V of Figure 1 showing details of the hydraulic jack in conjunction with the anchor bar in retracted position;

Figure 6 is a fragmentary detail of the quadrant gears taken in elevation on line VI—VI of Figure 1;

Figure 7 is a fragmentary detail of the quadrant gears in plan taken on line VII—VII of Figure 6;

Figure 8 is an enlarged fragmentary detail of the forward end of the cutter chain guide showing shoes in conjunction with the anchor bar; and

Figure 9 is an enlarged fragmentary detail of the forward end of the cutter chain guide in section on line IX—IX of Figure 8.

Reference is now made to the details of the machine of my invention illustrated in the drawings. The main frame 10 is pivotally mounted on a transverse cross member 11, which is formed integral with a pair of longitudinal endless-tread supporting side frames 12, 12, the side frames being provided with a front end idler sprocket or roller 13, a rear drive sprocket 14, fixed to a drive shaft 15 (source of power not shown) and an intermediate shoe 16 for endless treads 17, 17 of well known construction. A second cross member 18 is formed integral with the pair of side frames 12, 12. A pair of cylinders 19, 19 is pivotally mounted on the second cross member 18. A piston 20 is reciprocally mounted in each of the

cylinders 19, 19, the piston 20 being fixed to a piston rod 21 pivotally connected to the main frame 10. Hydraulic pressure to the cylinders 19, 19 for tilting the main frame 10 may be supplied as usual from a pump, under manual control of suitable valves, not shown.

Fixed to the forward end of the main frame 10 is a pair of cutting chain guides 22, 22. In each cutting chain guide 22, 22 is a cutter chain 23 of usual construction driven by a sprocket 24 fixed to a shaft 25. The drive shaft 25 is journaled in a housing 26 secured to each of the cutter chain guides (source of power not shown). Shoes 27, 27, fixed to top and bottom sides of the forward end of each cutter chain guide 22, 22, are adapted to bear against the top and bottom sides of the kerf to be described.

A single endless conveyor belt 28 is driven by a pulley 29, fixed to a drive shaft 30, the drive shaft 30 being journaled in the rear end of the main frame 10, source of power not shown. The conveyor belt 28 is trained over a pulley 31 journaled on a shaft 32 fixed in the forward end of the main frame 10, and in the path of the cutter chains 23, 23, the latter being adapted to rake and crowd the cuttings on the conveyor belt 28.

A pair of hydraulic jacks, each of which includes a cylinder 33, extends through and is fixed in each of the cutter chain guides 22, 22. A piston 34, reciprocally mounted in each of the cylinders 33, 33, is provided with a piston rod 35. A piston rod head 36, fixed to each of the piston rods 35, 35, is slidably guided in the end of the cylinders 33, 33 opposite the pistons 34, 34. A longitudinal slot 37 is provided in each of the cutter chain guides 22, 22, and an anchor bar 38 is pivotally mounted in each of said slots on a pin 39. The rear end of each anchor bar 38, 38 is formed to fit into each of the piston rod heads 36, 36. The forward portion of said anchor bars is adapted to engage and press against the floor of the mine, said anchor bars being actuated in a manner to accomplish this result by the piston rod heads 36 upon movement of the piston 34 in an upward direction. The cylinders 33, 33 are each provided with fluid inlet and exhaust pipes 40, 40 through which a pressure fluid may be supplied to the cylinders 33 for imparting movement to the anchor bars 38.

Mounted on the main frame 10 is a mechanism for breaking down the coal, similar to that shown and described in my prior United States Patent No. 2,368,863, dated February 6, 1945. This mechanism consists of a pair of spaced upright supporting brackets or bearings 41 and 42 and a pair of horizontal shafts 43 and 44 journaled therein. A pair of carriage guide members 45 and 46 is pivotally mounted at their rear ends on shaft 43. Quadrant gear 47, keyed to shaft 44, is meshed with quadrant gear 48, the quadrant gear 48 being integral with the guide members 45 and 46 so that rotation of shaft 44, by source of power not shown, will cause a swinging movement to the carriage guide members about the shaft 43. Guide members 45 and 46 are provided with bearing portions 49 and 50, respectively on which the ram bars 51 and 52, forming the sides of the carriage, are slidably mounted. The ram bars 51 and 52 are tied together to complete the carriage by a carriage base plate 53. The ram bars 51 and 52 are adapted to reciprocate on the bearing portions 49 and 50 and are provided with rack portions 54 meshed with rack pinions 55 keyed to the shaft 43, the shaft 43 being power driven in reversible directions by a source of power not shown. Secured to the carriage base plate 53 is a wedge plate 56 adapted to be driven into the coal at the mine face for dislodging the coal by successive thrusts of the wedge plate.

In operation the main frame 10 is fed forwardly to engage the cutter chains 23, 23 with coal to be mined

and thereby cut a kerf. Cuttings from the kerf are raked backwardly and crowded onto the conveyor belt 28 by the cutter chains. On completion of the cutting of the kerf to a predetermined depth, fluid is directed into the cylinders 33, 33 for imparting movement to the pistons 34, 34, and thereby cause the forward end of the anchor bars 38, 38 to be pressed against the mine floor previously cut by the cutter chains 23, 23.

As a result of the pressure exerted against the floor of the mine by the anchor bars 38, 38 as described, the forward end of the cutter guides 22, 22 is caused to bear against the top side of the kerf with an equal and opposite force. For this reason the cutter guides are provided with the shoes 27, 27 at their forward end and said shoes also reinforce the cutter guides during their cutting action in cutting a kerf. Thus the combined action of the anchor bars in pressing downwardly against the mine floor and that of the shoes on the forward end of the cutter guides in pressing upwardly against the top surface of the kerf locks the machine in a coal mining position and the reactive forces caused by the thrusts of the wedge plate are effectively resisted.

The forward end of the main frame carrying the cutter guides 22, 22 is adapted to enter the kerf to an extent whereby the said forward end is located beyond the material to be presently dislodged by the operations of the wedge plate 56. This is important since the action of the anchor bars 38, 38 is to thus cause said forward end of the main frame to engage solid material for holding the mining machine and which material is not dislodged by the reciprocating movements of the wedge plate to presently follow but remains intact, performing said holding function until the next succeeding operation of the mining machine.

Upon completion of the breaking down of the successive portions of coal to a predetermined height above the kerf the fluid in cylinders 33, 33 is released. The pressure in the cylinders 33, 33 being released, pressure on the anchor bars is removed and the anchor bars are reset in retracted position. With the anchor bars in retracted position, the machine is free to be moved forwardly to provide a successive kerf. When the machine is being moved forwardly for cutting the successive kerf, the broken down coal resting on the cutter chain guides 22, 22 is moved up inclined portion 57 of main frame 10 and onto conveyor belt 28 by reason of the cutter chain guides entering the successive kerf. The flared ribs 58, 58, forming part of main frame 10, are adapted to guide the flow of coal into the path of the conveyor belt 28 which extends longitudinally of main frame 10.

The invention is not to be limited to or by details of construction of the particular embodiment thereof illustrated by the drawings as various forms of the device will of course be apparent to those skilled in the art without departing from the spirit of the invention or the scope of the claims.

I claim:

1. In a mining machine having a main frame, a pair of cutter chain guides extending from said main frame, a drive sprocket in each of said guides, an endless cutter chain in each of said guides adapted to be trained over its respective sprocket, means for moving said cutter chains forwardly to cut a kerf in the material to be mined, a shoe disposed on the top side of at least one of said guides, an anchor bar pivotally mounted in at least one of said guides, breaking down mechanism mounted on said main frame for breaking down the material to be mined above said kerf and rearwardly of said shoe, means for imparting movement to said anchor bar for pressing said anchor bar into the bottom side of said kerf, said shoe being adapted to bear against the top side of said kerf with a force which is equal and opposite to that exerted by the anchor bar against the bottom side of said kerf, whereby said anchor bar and shoe provide an abut-

ment for resisting the reactive force of said breaking down mechanism.

2. In a mining machine having a main frame, undercutting means positioned at the forward end of said main frame and adapted to be moved forwardly to cut a kerf in the material to be mined, breaking down mechanism mounted on said main frame for breaking down material to be mined above said kerf, said forward end of said main frame being adapted to enter said kerf in advance of that portion of said kerf above which material is broken down by said breaking down mechanism, an anchor bar mounted adjacent the undercutting means at the forward end of the main frame for vertical swinging movement and being adapted to press into the bottom side of said kerf, said forward end of said main frame being adapted to bear against the top side of said kerf to provide a backing for said anchor bar, whereby said anchor bar provides an abutment for resisting the reactive force of said breaking down mechanism.

10 3. In a mining machine having a main frame, undercutting means positioned at the forward end of said main frame and adapted to be moved forwardly to cut a kerf in the material to be mined, said forward end of said main frame being adapted to enter said kerf, an anchor bar mounted adjacent the undercutting means at the forward end of the main frame for vertical swinging movement and being adapted to bear against the bottom side of said kerf, breaking down mechanism mounted on said main frame, said breaking down mechanism being adapted

15 30 to break down material to a predetermined depth but less than that of said kerf, whereby the material above the remaining depth of said kerf provides a backing for the anchor bar, said forward end of said main frame being adapted to bear against said backing with a force that is opposite to that exerted by the anchor bar when pressed into the bottom side of said kerf, whereby said anchor bar provides an abutment for resisting the reactive force of said breaking down mechanism.

35 4. In a mining machine having a main frame, undercutting means positioned at the forward end of said main frame and adapted to be moved forwardly to cut successive kerfs in the material to be mined, breaking down mechanism mounted on said main frame for breaking down material to be mined above each successive kerf, said forward end of said main frame being adapted to enter each successive kerf beyond the material to be broken down, an anchor bar mounted adjacent the undercutting means at the forward end of the main frame, means for imparting swinging movement to said anchor bar for pressing said anchor bar into the bottom side of each successive kerf, said forward end of said main frame being adapted to bear against the top side of each successive kerf to provide a backing for said anchor bar, whereby said anchor bar provides an abutment for resisting the reactive force of said breaking down mechanism.

40 5. In a mining machine having a main frame, a pair of cutter chain guides extending from said main frame, a drive sprocket journaled in each of said guides, an endless cutter chain in each of said guides adapted to be trained over its respective sprocket, means for moving said cutter chains forwardly to provide a kerf in the material to be mined, a shoe disposed on the top side of each of said guides, an anchor bar for each guide pivotally mounted in a slot provided in each of said guides, 45 50 55 a carriage mounted for vertical swinging movement relative to said main frame, a dislodging member mounted on said carriage and adapted to break down the material to be mined above said kerf and rearwardly of said shoes, a cylinder fixed to each of said guides, a piston mounted in each of said cylinders, each of said pistons being connected to the rear end of its respective anchor bar, said pistons upon actuation in a certain direction being adapted to press the forward end of said anchor bars against the bottom side of said kerf, and said shoes 50 55 being adapted to bear against the top side of said kerf

to provide a backing for holding said anchor bars against the bottom side of said kerf, whereby said anchor bars provide abutments for resisting the reactive forces of said dislodging member during operation thereof.

6. In a mining machine having a main frame, a pair of cutter chain guides extending from said main frame, a drive sprocket journaled in each of said guides, an endless cutter chain in each of said guides adapted to be trained over its respective sprocket, means for moving said cutter chains forwardly to provide a kerf in the material to be mined, at least one shoe being disposed on the top and bottom sides respectively of each of said guides, breaking down mechanism mounted on said main frame for breaking down the material to be mined, an anchor bar for each guide mounted in a slot provided in each of said guides, a cylinder fixed to each of said guides, a piston in each of said cylinders, each of said pistons being connected to the rear end of one of said anchor bars, said pistons upon actuation in a certain direction being adapted to press the forward end of said anchor bars against the bottom side of said kerf, and said shoes being adapted to bear against the top side of said kerf to provide a backing for holding said anchor bars against the bottom side of said kerf, whereby said anchor bars provide abutments for resisting the reactive force of said breaking down mechanism.

7. In a mining machine having a main frame, a pair of cutter chain guides extending from said main frame, a drive sprocket journaled in each of said guides, an endless cutter chain in each of said guides adapted to be trained over its respective sprocket, means for moving said cutter chains forwardly to provide a kerf in the material to be mined, at least one shoe being disposed on the top side of each of said guides and adapted to enter said kerf, an anchor bar for each guide pivotally mounted in a slot provided in each of said guides, breaking down mechanism mounted on said main frame adapted to break down the material to be mined above said kerf, means for imparting movement to each of said anchor bars for pressing said anchor bars into the bottom side of said kerf, said shoes being adapted to bear against the top side of said kerf to provide a backing for holding said anchor bars against the bottom side of said kerf whereby said anchor bars provide abutments for resisting the reactive force of said breaking down mechanism.

8. In a mining machine having a main frame, a pair of cutter chain guides extending from said main frame, a drive sprocket journaled in each of said guides, an endless cutter chain in each of said guides adapted to be trained over its respective sprocket, means for moving said main frame forwardly to force the operative sections of said cutter chains against the material to be mined to cut a kerf in the material to be mined, shoes disposed on the top and bottom sides of said guides adapted to enter said kerf, an anchor mounted in each of said guides, a breaking down mechanism mounted on said main frame adapted to break down the material

to be mined above said kerf and rearwardly of said shoes, said shoes being adapted to bear against the top and bottom sides of said kerf for guiding said operative sections of said cutter chain to cut said kerf in substantially the same plane as said shoes, said anchors being adapted to press against the floor of the mine relatively adjacent the rear of said shoes, and cause said shoes to press uniformly against the top side of said kerf, whereby said shoes are adapted to provide a uniform backing for holding said anchors pressed against the floor of the mine and thereby cause said anchors to resist the reactive force of said breaking down mechanism.

9. In a mining machine having a main frame, a pair of cutter chain guides extending from said main frame, an endless cutter chain trained in each of said guides and adapted to cut a kerf in the material to be mined, at least one shoe being disposed on the top side of each of said guides, breaking down mechanism mounted on said main frame adapted to break down the material to be mined above said kerf, at least one anchor bar mounted in each of said guides for vertical swinging movement relative to said guides, means for imparting swinging movement to said anchor bars for pressing said anchor bars into the bottom side of said kerf, said shoes being adapted to bear against the top side of said kerf to provide a backing for holding said anchor bars pressed into the bottom side of said kerf, whereby said anchor bars provide abutments for resisting the reactive force of said breaking down mechanism.

10. In a mining machine having a main frame, a platform extending from said main frame, at least one shoe disposed on the top side of said platform, undercutting means positioned at the forward end of said platform adapted to be moved forwardly to cut a kerf in the material to be mined, breaking down mechanism mounted on said main frame, said breaking down mechanism being adapted to break down the material to be mined above said kerf and rearwardly of said shoe, at least one anchor bar pivotally mounted in a slot provided in said platform, means for imparting movement to said anchor bar for pressing said anchor into the floor of the mine adjacent the kerf, said shoe being adapted to bear against the top side of said kerf to provide a backing for holding said anchor bar pressed into the floor of the mine, whereby said anchor bar provides an abutment for resisting the reactive force of said breaking down mechanism.
